(57) **CLAIM**

What is claimed is the ornamental design for a trolling motor propeller, as shown and described.

DESCRIPTION

FIG. 1 is an upper front perspective view showing the trolling motor propeller of Applicants' invention.

FIG. 2 is a lower rear perspective view of the trolling motor propeller of FIG. 1.

FIG. 3 is a front elevation view of the trolling motor propeller of FIG. 1.

FIG. 4 is a left side elevation view of the trolling motor propeller of FIG. 1.

FIG. 5 is a right side elevation view of the trolling motor propeller of FIG. 1.

FIG. 6 is top plan view of the trolling motor propeller of FIG. 1.

FIG. 7 is a bottom plan view of the trolling motor propeller of FIG. 1; and,

FIG. 8 is a rear elevation view of the trolling motor propeller of FIG. 1.
